Inventor:

Charles G. Conn.

By Knight Bros.

UNITED STATES PATENT OFFICE.

CHARLES G. CONN, OF ELKHART, INDIANA.

CORNET.

SPECIFICATION forming part of Letters Patent No. 402,721, dated May 7, 1889.

Application filed October 30, 1886. Serial No. 217,605. (No model.)

To all whom it may concern:

Be it known that I, CHARLES G. CONN, of Elkhart, in the county of Elkhart and State of Indiana, have invented an Improvement in 5 Cornets, of which the following is a specification.

My invention is an improvement in the connecting-pipes between the valve-cylinders. As heretofore constructed, these connecting-pipes have been either both straight or both curved, or one of them curved and the other diagonal.

In my improvement I substitute a straight pipe for the curved pipe in a curved and diagonal pipe-connection between the valves.

This improvement in construction makes the wind-passage more direct through the valves than with a curved and diagonal connection.

20 In order that my invention may be fully understood, I will proceed to describe it with reference to the accompanying drawing, which represents in section longitudinally of the valve-cylinders a portion of a cornet embodying my improvement.

The cornet is constructed with customary air-pipe, A, valve-bends B, and valve-cylinders 1 2 3. Connecting the valve-cylinders are pipes D D'—the first straight, as shown, to 30 present at d d right angles, while the second is made straight and arranged diagonally between the cylinders 2 3 from opposite the

valve-opening to pipe D to opposite the valve-opening to pipe A.

It will be observed that the position of the 35 connecting-pipes D D' may be reversed from that here shown, the diagonal pipe D' being arranged between the first and second valve-cylinders and the straight pipe D between the second and third valve-cylinders.

40 This invention is applicable to other piston-valve musical instruments as well as cornets.

Having thus described my invention, the following is what I claim as new therein and desire to secure by Letters Patent:

45 1. In a cornet or other piston-valve musical instrument, the combination, with the valve-cylinders, of a straight connection, D, between an outside valve-cylinder and the middle valve-cylinder, and a diagonal connection, 50 D', between the other outside valve-cylinder and the middle valve-cylinder, substantially as shown and described.

2. The combination, with the valve-cylinders 1 2 3, of a straight pipe-connection, D, between the first valve-cylinder, 1, and the second valve-cylinder, 2, and a diagonal pipe-connection, D', between the second valve-cylinder, 2, and the third valve-cylinder, 3, substantially as described.

CHARLES G. CONN.
